BAKERY TRAY

Robert F. Miles, Cincinnati, Ohio, assignor to MS
Industries, Inc., Cincinnati, Ohio, a corporation of
Ohio

Filed Apr. 12, 1967, Ser. No. 6,649

Term of patent 14 years

(Cl. D87—1)

Fig. 3

FIG. 4

FIG. 5

FIG. 6

FIG. 7

FIG. 8

FIG. 1 is a side elevational view of a bakery tray showing my new design;

FIG. 2 is a front elevational view thereof;

FIG. 3 is a fragmentary plan view thereof, a portion having been omitted for convenience of illustration;

FIG. 4 is a fragmentary section taken on line 4—4 of FIG. 2;

FIG. 5 is a fragmentary section taken on line 5—5 of FIG. 1;

FIG. 6 is a fragmentary section taken on line 6—6 of FIG. 1;

FIG. 7 is a fragmentary section taken on line 7—7 of FIG. 1; and

FIG. 8 is a perspective view thereof on a reduced scale, it being understood that the pattern in the bottom is continuous as in FIG. 3.

The side not shown and the rear are the same, respectively, as the side shown and the front.

I claim:

The ornamental design for a bakery tray, as shown and described.
